LICENSE PLATE HOLDER

Filed Dec. 31, 1930

UNITED STATES PATENT OFFICE

MADISON H. BENSON, OF AUSTIN, TEXAS

LICENSE PLATE HOLDER

Application filed December 31, 1930. Serial No. 505,912.

The present invention relates to vehicle tag holders.

An object of this invention is to provide a holder for receiving a conventional vehicle tag, the holder embodying means whereby the tag cannot be removed therefrom without destroying the tag so as to prevent removal of the tag from the holder and placing of the tag on another vehicle.

10 Another object of this invention is to provide a holder of this kind which may be mounted on a vehicle at any desired location and which will not interfere with the visibility of the numbers or letters on the tag and in 15 which any conventional tag may be inserted and sealed so as to prevent removal of the tag without destroying its value as a license tag for a vehicle.

20 A further object of this invention is to provide a tag holder of this kind which is readily and cheaply manufactured so as to permit the sale and manufacture of the device at a relatively cheap price.

The above and various other objects and 25 advantages of this invention will in part be described in and in part be understood from the following detailed description of the present preferred embodiment, the same being illustrated in the accompanying drawings, wherein:—

Figure 1 is a detail front elevation of a device constructed in accordance with the preferred embodiment of this invention;

Figure 2 is a sectional view taken on the 35 line 2—2 of Figure 1; and

Figure 3 is a sectional view taken on the line 3—3 of Figure 1.

Referring to the drawings wherein like numerals of reference designate corresponding parts throughout the several views, the numeral 10 designates generally a holder constructed according to the preferred embodiment of this invention, the holder 10 being constructed in substantially rectangular form and provided with a substantially rectangular-shaped opening 13 through which one face portion of the tag is exposed. The holder 10 may be constructed of metal and comprises a lower frame section 11, an upper frame section 12 and end sections 14. The

upper and lower frame sections 12 and 11, respectively, are constructed in substantially U-shaped form and constitute guides for slidably receiving a vehicle tag generally designated as 15. One of the end members 14 is 55 preferably open on the outer edge portion thereof, as at 16, and the other end may be closed, as at 17.

A securing plate 18 is secured to the lower frame member 11 and is provided with suitable apertures 19 for receiving securing bolts or the like so as to secure the frame 10 on the desired portion of the vehicle. One face of the frame 10 is provided with outwardly projecting recesses 20 which are pressed outwardly from the interior of the frame and the opposite leg of the frame sections is provided with an aperture 21 which is in alignment with the axis of the recess 20, this aperture 21 being provided so as to permit the projection of a tool in the form of a punch or the like therethrough for engagement with the tag 15 so as to press a portion of the tag 15 into the concave inner face portion of the recess 20. The use of the recesses 20 provides means for securing the tag 15 within the frame 10 and the tag 15 will remain within the frame 10 so long as the material of the tag is positioned within the concave inner surface of the recess. 80

It will be obvious from the foregoing that when the body of the tag adjacent the marginal edge portions thereof is forced into the recesses 20, the tag will be held against removal from the holder 10 and that in order 85 to remove the tag from the holder 10, it is necessary to practically destroy the tag inasmuch as the material from which the tag is made will not admit of a second bending or punching out of the original punched out 90 portion into the recess 20. The use of the frame herein disclosed will eliminate the necessity of using a securing bolt or the like for securing the tags to the holders but at the same time a holder has been disclosed which 95 may be readily cast of any desired metal.

While I have disclosed a plate or bracket member 18 secured to the bottom of the frame 10, I do not wish to be limited to this method of securing the frame 10 on the vehicle as if 100

desired, any other suitable form of bracket or securing member may be provided depending only upon the particular part of the vehicle to which the holder is to be secured.

5 In the use of this device, the tag 15 may be slid into the frame 10 through the slot 16 and when in such position as to expose the numerals thereof through the central portion 13, the holder may be laid down on a bench or table and a tool inserted through the openings 21. A portion of the tag will then be swaged or forced into the recess 20 as more clearly disclosed in Figure 2 at 22, and this swaged or pressed material will effectively hold the tag 15 within the holder against removal. 10 The instrument for swaging the tag is preferably of a blunt form so as not to pierce the body of the tag but it will, of course, be understood that even if the material of the tag is pierced, the pressed out portions thereof will effectively hold the tag within the holder 10 against removal.

15 In the present instance, there has been disclosed a plurality of recesses 20 which are mounted in longitudinally spaced position in the upper and lower frame sections 12 and 11, respectively, but I do not wish to be limited to this construction or positioning of the recesses as if desired, suitable recesses may 20 be formed on the end members 14.

25 As shown in the drawing, a screw 23 may be threadably mounted in the aperture 21 and this screw used for pressing a portion of the plate 15 into the recess 20. If desired, this 30 screw or bolt 23 may be left in the opening 21 so as to close the opening but I do not wish to be limited to this construction as if desired the screw 23 may be removed entirely and merely a plug screw inserted into the 35 opening 21 so as to close the opening and prevent dirt or the like from entering within the frame through this opening.

40 It will be obvious from this structure that either a punch or the screw or bolt 23 is used 45 to form the detent 22 in the license plate 15.

45 It is, of course, understood, that various 50 changes and modifications may be made in the details of construction and design of the above specifically described embodiment of 55 this invention without departing from the spirit thereof, such changes and modifications being restricted only by the scope of the following claims.

I claim:—

55 1. A license plate holder of the character 60 described, comprising a frame structure having a longitudinally disposed channel therein, said frame having a plurality of recesses in one face thereof, said recesses being adapted to receive pressed out portions of a license 65 plate.

70 2. A license plate holder of the character 75 described, comprising a frame having a longitudinally disposed channel therein where- 80 by to receive a license plate, said channel

85 opening outwardly through one end of the frame, a plurality of spaced recesses in one face of the frame, said frame having a plurality of openings in the opposite face aligning with the recesses whereby to permit the 90 insertion of a swaging tool for pressing a portion of the license plate into the recesses.

95 3. A license plate holder of the character 100 described, comprising a channeled frame adapted to receive a license plate, said frame having an opening in one end thereof whereby to permit the insertion of the plate within the frame, a plurality of recesses in one face of the frame and extending outwardly from the inside of the frame, said frame on the 105 opposite side having a plurality of apertures therein aligning with the recesses whereby to permit the insertion of a swaging tool for 110 swaging the license plate into the recesses, and bracket means for securing the frame 115 on a vehicle.

120 4. A license plate holder of the character 125 described comprising a channeled frame adapted to receive a license plate, a plurality of recesses in one face of the frame, said recesses providing a concave recess within the frame whereby to receive pressed-out portion of the plate lying oppositely from said recesses, said frame on the opposite side of 130 said recesses having an opening therethrough 135 and a member disposed within the opening.

140 In testimony whereof I hereunto affix my 145 signature.

MADISON H. BENSON.
